UNITED STATES PATENT OFFICE.

JOHN H. GOODFELLOW, OF LOWELL, MASSACHUSETTS, ASSIGNOR OF ONE-HALF TO JOSEPH W. PIPER, OF SAME PLACE.

COOKING OR HEATING APPARATUS.

SPECIFICATION forming part of Letters Patent No. 621,813, dated March 28, 1899.

Application filed June 23, 1898. Serial No. 684,318. (No model.)

To all whom it may concern:

Be it known that I, JOHN H. GOODFELLOW, of Lowell, in the county of Middlesex and State of Massachusetts, have invented a new and useful Improvement in Cooking or Heating Stoves, of which the following, taken in connection with the accompanying drawings, is a specification.

This invention relates to improvements in that class of stoves and ranges in which there is a combustion-chamber, an oven, and smoke-conducting flues about the same.

It relates more particularly to certain improvements for arresting the sparks and soot, thereby preventing their accumulation in the horizontal flues, and means permanently arranged in the flues, which may be operated at will to scrape the same.

The invention consists, primarily, of a chamber located beneath the rear vertical flues, a narrow passage connecting them with the chamber, and means substantially as described for closing the chamber and directing the products of combustion to the horizontal flue and preventing the passage of heat from one vertical flue to the other through the chamber, thereby forming a dead-air chamber in which the soot accumulates.

The invention further consists in the combination, with a chamber located beneath the rear vertical flues, of a passage connecting them with the chamber and a removable drawer or pan provided with a partition-plate registering with the dividing flue-strip of the vertical flue, and thereby prevent the passage of heat from one vertical flue to the other through the chamber in which the soot may automatically accumulate.

The invention further consists in a new and novel flue-scraper adapted to be permanently located in the flues, and means combined therewith for automatically moving their contact edges out of active position when moved in one direction, and means for operating and permitting said contact edges to automatically assume an active position when moved in an opposite direction over the surface to be scraped.

The invention further consists in the novel construction, combination, and arrangement of parts, such as will be hereinafter more fully

described, pointed out in the appended claims, and illustrated in the accompanying drawings.

In the accompanying drawings, in which 55 similar letters and figures of reference designate corresponding parts, Figure 1 is a perspective view, partly in section, of a range embodying my invention. Fig. 2 is a side elevation, partly in section, illustrating features in my invention. Fig. 3 is a sectional rear end view; and Fig. 4 is a top plan view of the same, taken below the bottom oven-plate, illustrating a modification of my invention.

Referring to the drawings by letters and figures, A represents the back or end plate; B, the bottom or base; C, the front jamb; x, the top, and y the front, oven-plate; D, the bottom oven-plate, and C² the rear oven-plate. 70 Between the two former and the two latter plates the flue-strips S and T are arranged, forming the horizontal flues O and P and vertical flues N and Q of an ordinary range.

As shown in all the figures of the drawings, 75 the bottom B is provided with narrow passages i² i², preferably beneath the vertical flues and beneath which the chamber f is permanently located, and its inlet-opening arranged at the front, as seen in Fig. 1, or side, 80 as shown in Fig. 2, or from its top side, as shown in Fig. 4, in which latter the extension J forms a low-down hearth provided with a hearth-plate k to close the chamber. The inner edge of this plate may be notched to straddle the flue-strip S, thus forming the cut-off i. These are adapted when the hearth-plate is in closed position to close the passages i² i², 85 communicating with the soot-chamber beneath, and need only to be withdrawn when the scrapers a are used or to relieve or discharge the soot accumulating at the junction of the flues or wholly withdrawn, as shown in Fig. 4, when it is desired to clear the chamber or remove the pan g, adapted thereto and provided with a suitable bail h. The upper, 90 rear, and side edges of this pan may pass beyond the overhanging edges of the passages i² i², thus leaving the passage narrower in width than that part of the chamber beneath the flue N or flues N and Q.

In some stoves where a sheet-flue is used

instead of the flues N and Q the extension *i* of the hearth-plate may be omitted and the edge of the hearth-plate constructed to abut the jamb A to close the chamber, leaving at 5 all times the said chamber in condition to automatically arrest the soot and cinders as they pass around the junction of the flues. In other stoves, and which are the most prevailing pattern, either two or three vertical flues are 10 used, forming ascending and descending flues, which if provided with my improved soot-collecting chamber may be made automatic by using the partition 7, forming an extension of the flue-strip S into the chamber, 15 the main object of which is to prevent any connection between the vertical flues through the said chamber, and the preferred form, construction, and arrangement are that the passages i^2 i^2 shall always be open, as plainly 20 shown in Figs. 1 and 2, whether the rear vertical flue be of a sheet-flue or diving and ascending flue construction. In regard to the application of this feature of my invention the said partition-plate may be permanently located in the chamber *f*, and thus divide it into individual chambers, one beneath each flue, and each chamber may be supplied with a suitable pan or drawer, if desired, or the said partition-plate may be located 25 in the pan, as shown in Fig. 1, its upper edge registering with the strip S, or its extension 8 cast on the bottom B at the division-line of said vertical flues. The front end of said pan *g* may have its end closed 30 with a suitable casting, which may correspond with the skirting, so that when placed in position within the chamber *f* the said partition-plate 7 will register with the strip and the casting register with the skirting and 35 close the inlet to the flue and chamber. Referring to Fig. 2, the said partition-plate is likewise placed in the pan in line to register, which registering is effected edgewise with the extension 8, and one side of the pan 40 formed or attached to a part of the removable skirting, which when in position closes the chamber.

Referring to Figs. 3 and 4, which show the modified form, the extended hearth *J* forms 45 a part of the chamber *f* and is closed by the hearth-plate *k* sliding over it, and if the said partition-plate be located permanently within the chamber, thus forming two or more 50 chambers, which may or may not be provided with a pan, or the said partition-plate located 55 in the pan in a position to register with the said vertical flue strip or strips and the said hearth-plate fitted to slide over its upper and outer edge of the same, so that when in closed 60 position its inner edge *i* will register with the jamb A and effectually close the top of the chamber, but leave each division-chamber connected with the vertical and horizontal flues through the passages i^2 i^2 , by means of 65 which dead-air chambers are formed beneath the vertical flues. An eddy or vortex formed therein by the passing currents of combus-

tion deposits the soot and ashes automatically within the chambers.

In the flues O and P, I preferably arrange 70 the flat scrapers *a a*, which extend across the path of the horizontal flues. Centrally between their ends I pivotally connect the rod *b*, which extends through the hole *b* in the wall A. To their outer ends I attach a suitable operating-knob *d*, by which the scraper may be moved forward and backward through the flue-passage, conveying the soot before it to the passages i^2 i^2 . It is desirable that these 75 flue-scrapers be made automatic so far as 80 their action on the bottom of the flue is concerned. To provide this means, I provide each scraper with the curved members *r r*, cast to the rear bottom edge, practically forming 85 a segment of a wheel, thus adapting them to readily roll on the periphery of said members, the office of which is to lift the bottom edge of the scraper out of contact whenever pushed back by the rod *b*. Centrally between 90 the ends of the blades *a* a suitable pivot connection is established which will permit the blade to turn upon the end of the rod in the line of travel. As shown, they are adapted 95 to turn from an obtuse to a vertical position and are retained at right angles to the rod by 100 the guides *t*, which extend from one side of the blade sufficient to support the slot *t* a short distance from the pivot, the rod closely fitting the slot, the length of which being sufficient to permit the blade to turn, as desired, upon the members *r r*, the upper and 105 lower ends of said slot acting as stop to retain it in its varied positions as it is pushed or pulled through the passage. Thus it will be seen that the said scraper can only act to 110 scrape the flue when drawn forward, and the act of pushing it back rolls the blade out of contact with the bottom of the flue, the curved members supporting it in raised position.

Having thus described my invention, what I claim is—

1. A scraper device consisting of a suitable plate or blades, means combined therewith for automatically moving their scraping edges out of active position when moved in one direction and means for operating and permitting said scraping edge to automatically assume an active position, when moved in an opposite direction over the surface to be scraped.

2. A flue-scraper, consisting of a suitable plate or blade, means combined therewith adapted to permit said blade to roll or rock in the line of travel, and having an operating-rod pivotally connected thereto, constructed and arranged at its pivotal connection so as to adapt it to permit said movement over the path on which it is arranged to travel.

3. A flue-scraper, consisting of a suitable plate or blade provided with rocking members extended from the bottom edge of one side of said plate or blade, adapted to support the said blade out of scraping contact,

and an operating-rod pivotally connected thereto intermediately of its length, and furnished with means adapted to permit the blade to assume varied positions when operated, substantially as described.

4. A flue-scraper, consisting of a suitable plate or blade, provided with means adapted to permit the blade to roll or rock in the line of travel, an operating-rod pivotally connected thereto intermediately of its length, and furnished with means adapted to permit said blade to assume varied positions, and means for maintaining the blade at right angles to the rod, substantially as described.

5. In combination with a cooking-stove provided with a rear end vertical diving flue and a connected horizontal flue and connected ascending flue, of a chamber permanently located beneath the former, and having a longitudinal slotted opening connecting them together, and furnished with a device for closing the chamber and providing access thereto, whereby a dead-air chamber is established, and an eddy formed by the passing currents as set forth.

6. In combination with a cooking-stove provided with rear end vertical diving flue, a connected horizontal flue, and rear side ascending flue, of a chamber permanently located beneath the former provided with a longitudinal slotted opening connecting them together of a smaller diameter than the width of said chamber, adapted to overhang the upper edge thereof, and furnished with a device for closing and providing access thereto, said chamber, whereby an eddy is formed by the passing currents and the sparks prevented from leaving the chamber as set forth.

7. In combination with a cooking apparatus provided with a rear end vertical diving flue, a connected horizontal flue and a connected ascending flue, a chamber permanently located beneath the former, a longitudinal slotted opening connecting them together, of smaller diameter than the width of said chamber, adapted to overhang the upper edge thereof, of a pan or drawer adapted thereto arranged in a position to receive the soot from the flues, and furnished with a device for closing and providing access thereto, combined to operate as set forth.

8. In combination with a cooking apparatus provided with rear end vertical ascending and descending flues, and connected horizontal flues, a chamber permanently located beneath the vertical flues, and having a longitudinal slotted opening connecting each of them with

the chamber, of a partition located in said chamber constructed and arranged and adapted to register with the dividing flue-strip of the vertical flues, whereby the same are extended to form a dead-air chamber for its individual flue, and means for closing and providing access thereto as set forth.

9. In combination with a cooking apparatus provided with vertical ascending and descending flues, and connected horizontal flues of chambers permanently located beneath the former flues, and having their division formed by a dividing-partition registering with the dividing flue-strip of said vertical flues, and furnished with longitudinal slotted openings connecting them with their respective flues, and a pan or drawer adapted to each thereof, and means for closing and providing access thereto, combined to operate as and for the purpose set forth.

10. In combination with a cooking apparatus provided with rear vertical diving flue and ascending flue and connected return horizontal flues, a chamber permanently located beneath the vertical flue, of a drawer or pan adapted thereto provided with a vertical partition within said pan arranged in lines parallel to register with the dividing-plate of the horizontal flue, one of its walls registering with the skirting.

11. In combination with a cooking apparatus, provided with rear end vertical diving flue, and ascending flue and connected horizontal flues, of a chamber permanently located beneath the rear vertical flues, having longitudinal slotted openings connecting them with the chamber and of smaller diameter than the width thereof, adapted to overhang the upper edge of a pan or drawer therein, an extension on the bottom of the stove forming a continuation of the dividing flue-strip, a partition in the pan or drawer adapted to register therewith means for closing the chamber and providing access thereto, whereby connection between the vertical ascending and descending flues is cut off, but continued to the horizontal flues, an eddy formed at the junction by the passing currents, as and for the purpose set forth.

In testimony whereof I have set my hand, this 13th day of June, 1898, in the presence of two subscribing witnesses.

JOHN H. GOODFELLOW.
